UNITED STATES PATENT OFFICE.

RICHARD WEBB BURNETT, OF MONTREAL, QUEBEC, CANADA.

DUMP-CAR DOOR.

1,079,691.

Specification of Letters Patent.

Patented Nov. 25, 1913.

Application filed December 14, 1910. Serial No. 597,183.

To all whom it may concern:

Be it known that I, RICHARD WEBB BURNETT, a citizen of the United States of America, residing at No. 42 The Linton, 5 Montreal, Province of Quebec, Dominion of Canada, have invented certain new and useful Improvements in Dump-Car Doors, of which the following is a specification.

My invention relates to dump car doors 10 used in connection with cars in which the material such as grain, ore or coal is conveyed in bulk.

The object of my invention is to provide a door of this type of simple and strong 15 construction and adapted to entirely prevent leakage even when the main portion of the closed door fails to make contact with the door frame.

The invention may be said broadly to consist of a hinge joint for the door for retaining the contents of a car, against the pressure due to its tendency to discharge, such 20 joint being constructed and arranged to tighten in proportion with the said pressure.

The invention further consists of an 25 apron carried by the free end of the door and adapted to form an extension chute when the door is open and a sealed closure when closed.

A further object is to provide a continuous hinge to a door which increases the strength of the door and which prevents any leakage.

Hitherto it has been the practice to hinge 30 the doors of dump cars at the ends or at intervals along the door edge. With such a construction there has always been more or less leakage between the door and frame 35 at the hinge.

With my construction a continuous hinge 40 extends along the entire edge of the door. This hinge is preferably constructed from the metal plates of which the door and its frame are made, the adjoining edges of the door and the door frame being bent and the bent portions engaged. The result is a hinge with a limited play but sealed for the 45 whole of its length. The bent portions moreover greatly strengthen the frame and the door. The apron is hinged to the door in a similar manner and as before mentioned provides an extension chute to the door when open and a sealed closure when 50 the door is closed.

Reference is made to the annexed drawing in which:

Figure 1. shows a perspective view of one form of hinge. Fig. 2. shows a modified form of hinge. Fig. 3. shows in section a dump car with a hopper fitted with a door and apron as will be described below.

In Fig. 1. an ideal form of the hinge is shown. A, represents the frame or floor and B, the door. The bent edge D, of the frame A, meshes with the bent edge C, of the door B. In this form the bent portions appear in the shape of spiral curves. As however the constructional difficulties of bending the edges of metal plates to true spiral curves are considerable, a modified form as shown in Fig. 2. can be employed and this is of simple and easy construction.

Other modifications of the form of the bends may be made without affecting the mode of operation.

In addition to the bends of the edges a flange N may be secured to either the door or the frame to limit the play of the hinge.

In Fig. 3. is shown the center sill H of a dump car with a hopper wall A resting on it. To this hopper wall A is hinged the door B which when closed assumes a horizontal position and when open forms a continuation of the slope of the hopper wall A. To the edge F of the door is hinged the edge G of the apron E which when drawn up by the closing mechanism L forms a sealed closure with the edge K of the side sill J and when released forms an extension chute to the door B.

It is to be specially noted that the apron E forms a sealed contact with the sill J as soon as they are drawn together by the chain M, and although the apron E has not been drawn entirely home. In this feature my invention overcomes a difficulty that has long existed in the closure of dump car doors.

In the ordinary construction of the hinges of these doors, the hinge is an element of weakness in the structure, and increases the cost of maintenance. Whereas in the present device the hinge is an element of strength as it is equivalent to a flange or corrugation and gives the door a continuous and unbroken support for its entire length. Moreover there are no loose parts or parts that may become loose, and the wear will not decrease the efficiency but will on the contrary.

make the contact surfaces more accurate and tighter fitting. It will also appear that with this device the greater the load the tighter will be the joints making a positive seal.

5 In the construction of this device the usual side flanges to both door and apron will be provided. Stops to limit the swing of the door and apron will also be provided 10 if necessary.

10 The means of closing the door and apron may be varied but I illustrate a simple and effective form consisting of a chain M adapted to wind on a bar provided with a ratchet 15 or clutch and a crank L.

15 The improved hinge members may be made independently of the door and frame and fastened thereto, within the scope of my invention.

20 Having now described my invention and its mode of operation what I claim and desire to secure by Letters Patent is:—

1. In a dump car a central sill, a hopper wall secured thereto, a hopper door hinged 25 to the hopper wall by means of their intermeshing bent edges, an apron hinged to the hopper door by means of their intermeshing bent edges, a side sill against which the apron rests when closed and means to open 30 and close the hopper door and apron, as described.

2. In a dump car, a hopper door hinged to the hopper wall by means of their intermeshing bent edges, an apron hinged to the 35 hopper door by means of their intermeshing bent edges and means to open and close the apron and hopper door, as described.

3. In a dump car a hopper door, an apron hinged thereto by means of their intermeshing bent edges, a sill against which the apron rests when closed, and means to open 40 and close the hopper door and apron as described.

4. In a dump car a floor plate provided 45 with an edge bent downwardly and curved beneath the same, a door plate having an edge bent upwardly and curved to overhang the same the said upwardly bent edge meshing with the downwardly bent edge of the 50 floor plate and forming therewith a continuous hinge for the door as described.

5. In a dump car a hopper door hinged to

the floor plate by means of their intermeshing bent edges—and an apron hinged to the hopper door by means of their intermeshing 55 bent edges as described.

6. In a car the combination with a floor plate one edge of which is bent downwardly and curved beneath the same, of a door plate one edge of which is bent upwardly and 60 curved to overhang the same and adapted to engage and be supported by the curved edge of the floor plate.

7. In a car, a door frame, one side of which forms a floor plate, in combination 65 with a hopper door hinge consisting of the intermeshing upwardly curved edge of the door plate overhanging the same, and the downwardly curved edges of the adjacent floor plate, as described.

70 8. In a car for containing loose commodities the combination with a door frame, one side of which is formed by a floor member, and a door, of a hinge extending continuously throughout the hinged edge thereof 75 and consisting of a pair of members presenting engaging bent edges, one of such members being upon the floor and having one edge bent downwardly and curved beneath the same, and the other upon the door and 80 having one edge bent upwardly and curved to overhang the same.

9. The combination with the door frame of a car for containing loose commodities one side of such frame consisting of a floor 85 member and a door for such frame, of a hinge extending continuously throughout the hinged edge thereof and consisting of a pair of members one upon the floor member and having one edge bent downwardly and 90 curved beneath the same and the other upon the door and having one edge bent upwardly and curved to overhang the same the edges of such members engaging one another and constructed and arranged to tighten in proportion 95 with the load sustained thereby.

Signed at Montreal this twenty first day of November, 1910, in the presence of two witnesses.

RICHARD WEBB BURNETT.
